UNITED STATES PATENT OFFICE.

SMITH MADISON JOHNSON, OF MIDDLEFIELD, OHIO.

WIRE TWISTER.

Application filed January 5, 1922. Serial No. 527,193.

To all whom it may concern:

Be it known that I, SMITH MADISON JOHNSON, a citizen of the United States, and a resident of Middlefield, in the county of 5 Geauga and State of Ohio, have invented certain new and useful Improvements in Wire Twisters, of which the following is a specification.

My invention relates to improvements in 10 wire twisters, and it consists in the constructions, combinations and mode of operation herein described and claimed.

An object of the invention is to provide a simple device for twisting the wires which 15 hold the tops of candy pails in place.

Another object of the invention is to provide a simple, portable, hand-operated tool which has simply to be set on the wires of a candy pail and given a few turns in order 20 to twist the wires and so hold the top in place.

Other objects and advantages will appear in the following specification, reference being had to the accompanying drawing, in 25 which:—

Fig. 1 is a perspective view illustrating the application of the wire twister.

Fig. 2 is a perspective view of the wire 30 twister alone,

Fig. 3 is a detail diagram illustrating the wire twisting action,

Fig. 4 is a detail section on the line 4—4 of Fig. 2,

Fig. 5 is a detail view of the twister pinion 35 illustrating a modification wherein two wire slots are used instead of one, and

Fig. 6 is a perspective view of a further modification, illustrating the use of a counter.

40 The purpose of the invention is to twist the wires 1 and 2 of the candy pail 3. This pail is made of wood, and has a wooden cover 4 which is held in place when the pail is filled, by the wires 1 and 2. The ends of 45 these wires are suitably affixed to the sides of the pail. The bights of the wires are brought together, and the usual manner of twisting or tightening them is to insert a nail and give the wires a sufficient number 50 of turns to produce the required tension.

The wire twister accomplishes the same purpose but employs a simple mechanism which does the work much more quickly and far better. It comprises a frame or casing 5 with a handle 6 on the outside. The shaft 7 of this handle carries a pinion 8 which drives

an idler 9. The idler in turn drives a twister pinion 10 which has a slot 11 into which the wires 1 and 2 fit without passing. The handle 6 is given a number of turns (usually 60 four or five) whereupon the twister pinion 10 twists the strands of wire into the shape shown at 12 in Fig. 3.

An improvement of importance comprises the pawl 13 which prevents the pinion slot 65 11 from passing corresponding slots 14 in the casing 5 on a reverse motion of the handle 6. At such time a pin 15 on the pinion 10 engages the end of the pawl. Obviously, it is only necessary to turn the handle 6 70 back until it stops, in order to find the slot 11 or bring it into registration with the slots 14. It is necessary to do this in order to get the wires 1 and 2 into the pinion.

A spring 16 draws the pawl 13 against a 75 stop 17. The pawl is pivoted at 18. The pin 15 moves the pawl aside when the handle 6 is turned in the clockwise direction indicated by the arrow.

The twister pinion 10 has circular shoulders or hubs 19 which furnish it bearing in the side plates of the casing. The slots 14 in the casing sides have beveled approaches 20 which facilitate fitting the tool over the wires 1 and 2.

80 A modification of the twister pinion 10 consists in providing two slots 11^a (Fig. 5) instead of only one as in Fig. 3. Either arrangement works well, but the form in Fig. 3 is preferred largely on account of its simplicity. In the case in Fig. 5, care must be taken to get the wire strands 1 and 2 in the individual slots. Turning the pinion 10 causes the twisting of the wires, as in Fig. 3.

85 A further modification consists in adding 90 a counter 21 as in Fig. 6. This counter may be actuated in any suitable manner by any moving part of the tool. The arrangement shown is simply for the purpose of illustration and consists of a cam 22 on the crank 100 shaft 7, the cam being intended to periodically strike a lever 23 of the counter. The purpose of the counter is to keep an account of the number of times that the tool is used. For example, the tool may be rented 105 to a user who may be required to pay in accordance with the number of pails he has sealed.

I claim:—

1. A wire twister comprising a casing to 110 be carried in the hand, a handle actuating gears on the inside of the casing including

22

a pinion having bearing in the walls of the casing and having a slot registerable with 5 passages opening to an edge of the casing, a pawl pivoted on the casing having a spring pulling it against a stop, and a pin carried by said pinion, passing the pawl when rotated in a wire-twisting direction but engaging the end of the pawl when reversely rotated, to indicate the registration of the slot 10 with said passages.

2. A wire twister comprising a casing having a wire-receiving passage, a revoluble member having a slot, means to revolve said member in one direction to bring the slot and 15 passage into registration to receive the wire and in the other direction to twist the wire, a pawl carried by the casing, means to draw the pawl in one direction, means to stop the pawl in a predetermined position in respect 20 to the revoluble member, and means carried by the revoluble member to engage the pawl and be stopped thereby in the wire-receiving position but passed under the pawl in the wire-twisting operation.

25 3. A wire twister comprising a casing having a wire passage at one edge, a revoluble member housed by the casing having a slot, means housed by the casing and having actuating means on the outside to revolve said member in one direction to bring the slot and passage into registration to receive the wire and in the other direction to twist the wire, a pawl pivoted on the casing, means carried by the casing and attached to 30 the pawl to draw the pawl in one direction, means on the casing to stop the pawl in a predetermined position in respect to the rev-

oluble member, and means carried by the revoluble member to engage the pawl and be stopped thereby in the wire-receiving position but passed under the pawl in the wire-twisting operation. 40

4. A wire twister comprising a casing having a wire passage opening at one edge, a pinion housed by the casing provided with 45 hubs by which it is journaled in openings in the sides of the casing, and having a slot, gears housed and journaled in the casing for driving the pinion, means on the outside of the casing to turn the gears and pinion in one direction to bring the slot into registration with the passage to receive the wire and in the other direction to twist the wire, a pawl pivoted outside of the casing having a spring to draw it against a stop on the casing and into a predetermined position in respect to the adjacent pinion hub, and means projecting from said hub to engage the end of the pawl and be stopped thereby in the wire-receiving position but pass under the pawl 55 in the wire-twisting operation.

5. A wire twister comprising a casing, a pinion having hubs journaled on the casing and being slotted for wire twisting, means 60 carried by the casing to revolve the pinion in two directions, means projecting from one of the hubs, and means on the casing to be engaged by the projecting means and stop the pinion in a wire-receiving position when revolved in one direction but to be passed 65 under when the pinion is revolved in the other direction in a wire-twisting operation.

SMITH MADISON JOHNSON.
